JEROME B. WITHEY, OF LEXINGTON, MICHIGAN.

Letters Patent No. 73,941, dated January 28, 1868.

IMPROVEMENT IN RUNNING-GEAR FOR CARRIAGES.

The Schedule referred to in these Letters Patent and making part of the same.

TO WHOM IT MAY CONCERN:

Be it known that I, JEROME B. WITHEY, of Lexington, in the county of Sanilac, and State of Michigan, have invented a new and useful Improvement in the Running-Gears for Carriages and Wagons; and I do hereby declare that the following is a true and accurate description thereof, reference being had to the accompanying drawings, and to the letters of reference marked thereon, and making a part of this specification.

The advantages of my improvement are as follows:

First. In using the ordinary wooden wheel, but without a box in the hub, the hole in the hub being fitted with a solid iron bar, held firmly in its place by the nut at the end of the hub. By this means I secure a much stronger and more durable hub.

Second. It is never necessary to remove the wheel for the purpose of oiling, the journals being oiled in the ordinary way through a hole in the upper side of the journal-boxes.

Third. The journals are perfectly protected from all dirt or grit, and consequently will outlast any running-gear constructed in the ordinary way.

Fourth. My invention will cause a carriage to run silently, there being nothing about it that can rattle or clatter.

Fifth. It will be less liable to get out of order, and, in case of accident, more readily repaired than the ordinary running-gear.

Sixth. The readjustment of the wheels is greatly facilitated by the ease with which the boxes may be set in any position.

Seventh. With his wheels ready made, timbers bent, and spindles or journals and boxes prepared, almost any man can in a few hours put together his own running-gear.

Eighth. The weight being thrown upon the main journals at the hub, the same supporting power is secured, by the use of at least one-quarter less weight of timber than in the ordinary way.

Ninth. It can be built at less than one-half the cost of the ordinary running-gear.

Tenth. It will be elegant in appearance, easily painted, and easily washed when required, and much more easily handled by the team.

Having thus set forth the benefits, or at least some of them, which I think will arise from the use of my invention, I will now describe its manufacture, so that those skilled in the art can make it, especial reference being had to the drawings.

Are wrought spindles or journal-shaft, which are driven into and fitted into the hubs B, and are held firmly in place by a suitable collar on the inner end of the hub, and by the nuts C on the end of the shaft A. D are proper boxes, in which run the journals of the shaft A. E is a light bar, of wood or iron, forming one half of a circle, near the ends of which, and on the under side, are placed the boxes D, secured by proper bolts. F is a light bar connecting the ends of the half circle E, and possessing sufficient strength to support the weight brought upon it by the supporting bar G, which runs from E to F, and to which is attached the box in which runs the inner end of the shaft A. H is a light bar connecting E and F, completing the framework for the forward wheels. I is a light bar, of wood or iron, bent at the end, so as to form a convenient resting-place for the outside box for the hind wheel. J is the reach, the after part being split, and the arms diverging in a curve, and connected with the bar I at the ends. The forward end is attached to the bar H by a proper bolt, thus making a reach as well as a portion of the framework for the hind wheels. K is a light bar, supporting the small or inner end of the shafts A of the hind wheels. L is a plate of iron, fitted to the upper side of the circle E, and projecting over the inside edge of the circle, coupling it with the reach J, by means of a simple dog, M, the lip or flange of the dog passing under the projecting edge of the plate L, thus forming a simple, and neat, and effective coupling. N are light draught-rods, drawing straight from the wheel. By this arrangement the weight and strain of draught are removed from the centre of an axle, as in ordinary carriages, and applied directly near the hub. The pole or shafts for the horse or horses should be attached to the inside of the circle E, near the ends, and just forward of the boxes D.

What I claim as my invention, and desire to secure by Letters Patent, is—

The combination and arrangement of a running-gear for carriages, as hereinbefore described, when constructed with the wrought spindle or journal-shaft A, the hub B, a collar and nut C, boxes D, bars E, F, G, H, I, and K, reach J, plate L, dog M, and draught-rods N, when put together and operating substantially as and for the purposes set forth.

JEROME B. WITHEY.
